WINDOW STOP STRIP MOUNTING

Harry W. Lane, Syracuse, N. Y.

Application March 3, 1937, Serial No. 128,849

6 Claims. (Cl. 20—12)

This invention appertains to so called stop strips or molding strips for windows and the like, and has for its primary object the provision of an improved fastening device assembly for such strips, whereby to normally yieldably urge the strips into close engagement with the window sash.

In carrying out the above mentioned principal aim of the invention, it is an object of the invention to simplify the construction of such stop strips and their fastenings so that the stop strips may be conveniently mounted on the window frame, or removed therefrom, at will, and with a minimum amount of labor.

15 The invention further contemplates the provision of one or more fastening assemblies for each stop strip, which assemblies include a fastening device such as a wood screw or the like, a cup-shaped washer having a transversely elongated slot in the base thereof through which the screw is adapted to extend, and a coil spring having one end disposed in abutting engagement with the screw, and its other end received within a tubular socket member, the latter being provided with a 20 offstanding spur adapted to be embedded in the stop strip.

25 A still further object of the invention is to provide an improved type of housing or socket for the coil spring which forms a part of the mounting assembly mentioned above, said springs and sockets being preferably received in suitable recesses provided therefor in the rear face of the stop strip, and when mounted therein, being concealed from view, while at the same time, acting to positively urge the stop strip into firm frictional engagement with the window sash, and prohibiting the sash from rattling, and also acting to produce a weather-sealing action through such yieldable engagement of the stop 30 strip with the sash.

35 Other and further objects and advantages of the invention will be hereinafter described, and the novel features thereof defined by the appended claims.

40 45 In the drawing:—

Figure 1 is a vertical sectional view taken through a typical window frame structure having double-hung sashes, said structure having my invention incorporated therein;

50 Figure 2 is an enlarged fragmentary horizontal sectional view taken approximately on the line 2—2 of Figure 1;

55 Figure 3 is an enlarged detail view in perspective illustrating the stop strip fastening assembly, with the parts thereof separated so as to

show their relationship in assembling the same; and

Figure 4 is an enlarged fragmentary perspective view of a portion of one of the stop strips, as viewed from the rear face, to show the recess formed therein and in which the parts of the fastening assembly are received.

Like reference characters designate corresponding parts in the several figures of the drawing.

In Figure 1, 1 generally designates a window frame which may be of any standard construction or otherwise, and in which are mounted two sliding sashes 2 and 3, in the usual manner of double-hung sashes. At the opposite side of the sashes, there are provided stop strips or molding strips 4 which extend vertically of the window frame 1 on the inner faces thereof at each side. According to my invention, these strips are mounted so as to be movable laterally towards and away from the contiguous faces of the 20 sashes 2 and 3, respectively, and suitable means is provided to normally urge the stop strips 4 into close frictional contact with the sashes.

As will be seen from the various figures of the drawing, each stop strip 4 is provided with a series 25 of openings or apertures 5, arranged in spaced relation to each other, and leading laterally from these openings 5, and formed in the rear face of the stop strip are recesses 6, the purpose of which will hereinafter more fully appear.

30 Mounted in the openings 5 at their inner ends, are cup-shaped washer members, generally designated 7, the marginal edges of which are turned over and are provided with one or more spurs 8 adapted to be embedded into the face of the 35 stop strip so as to prevent rotation of the washer members 7 when the same are mounted in the openings 5. The bottom wall 9 of each washer member is provided with an elongated slot 10 which is arranged to extend in a generally trans- 40

verse direction respecting the stop strip, when the cup-shaped washer is applied thereto. A fastening device, such as a wood screw 11, extends through the slot 10 of each washer member 7 and extends into the window frame 1 upon which the 45 stop strip is mounted. The screws 11 are screwed into the frame 1 only far enough to hold the stop strip 4 close against the frame 1, and sufficient looseness is afforded to allow for lateral movement of the stop strips 4 towards and away from 50 the window sash, such lateral movement being permitted by reason of the provision of the elongated slots 10 provided in the washer members 7. The assembled relation of these parts is best 55 seen in Figure 2.

Mounted within each of the recesses 6 in the rear face of the stop strip 4, is a helical or coil spring 12, one end of which is adapted to abut against the shank of the screw 11, and the other end of which is received within a tubular socket member 13, which is preferably closed at its end, as at 14, to provide a seat for the end of the spring. The socket member is provided at its closed end with an offstanding or laterally extending spur 15 which is adapted to be embedded in the base of the groove 6, near its end which is farthest from the opening 5, this spur 15 serving to anchor the socket member 12 to the stop strip and transmit the pressure of the spring 12 to the stop strip whereby to positively normally urge the stop strip laterally towards the sash and afford close frictional contact between the edge 16 of the stop strip and the sash. As will be best understood from reference to Figures 2 and 3 of the drawing, the axis of the coil spring 12 and its tubular socket member 13 is disposed at substantially a right angle to the axis of the screw 11 and washer member 7, and when the parts are assembled as shown in Figure 2, the spring and socket member 13 are concealed from view, and cannot become accidentally displaced.

The construction just described admits of quick and easy assembly and disassembly of the parts, and attains the desired yieldable action of the strip at a very nominal cost, owing to the simplicity of the construction and of the several parts which make up the fastening assembly illustrated best in Figure 3. Obviously, the parts of the fastening assembly may be made and sold in large quantities at a very low cost, and readily lend themselves to distribution to the public through so called chain stores, as well as through building hardware dealers. The fastening assembly is moreover applicable to window stop strips already installed, as well as to new installations, and little or no skill is required to provide the openings 5 and recesses 6 in the stop strips to accommodate the same to my improved type of fastening assembly.

In providing the socket member 13, a more positive yieldable action of the spring is assured, and the tendency of the spring to cause excessive friction between the stop strip and the window frame, or to buckle, is materially reduced and virtually eliminated. This socket member may be made from any suitable tubular metal stock, or it may be stamped in one piece from a sheet metal blank and subsequently bent into tubular form, and the spur-forming portion thereof bent across the end of the tube to close the same and provide the offstanding spur-like projection 15, which, when embedded in the base of the recess 6 at the rear side of the stop strip, positively anchors the socket member 13 to the stop strip, and prevents axial movement of the socket member within the recess 6.

The operation of the invention and its manner of assembly should be obvious from the foregoing description, and therefore need not be further described.

While the specific details of construction have been herein shown and described, the invention is not confined thereto, as changes and alterations may be made without departing from the spirit thereof as defined by the appended claims.

Having thus described my invention, what I claim as new and desire to secure by Letters Patent is—

1. The combination with a window frame having a sash slidably mounted therein, of a mold-

ing strip movably secured to said frame at one side of said sash, and means for normally yieldably urging said strip towards said sash, said means including a coil spring recessed in the rear face of said molding strip and having one end thereof received within a socket member adapted to be anchored to said molding strip within said recess, and a fastening member extending through said molding strip and into the contiguous face of the window frame and against which one end of the spring aforesaid is adapted to abut, there being sufficient looseness afforded between the fastening member and the molding strip to permit relative movement therebetween in a lateral direction.

2. The combination with a window frame having a sash slidably mounted therein, of a stop strip movably secured to said frame at one side of said sash, and means for normally yieldably urging said strip towards said sash, said means comprising a screw extending through said strip and into said frame, and respecting which said strip is laterally shiftable, a coil spring mounted in a recess formed in the rear face of said strip, one end of said spring abutting against the screw aforesaid, and a tubular spring socket also mounted in the recess aforesaid and in which the opposite end of the spring is adapted to be received, said socket member being provided with an offstanding spur adapted to be embedded in the base of the recess in the rear face of the strip.

3. The combination with a window frame having a sash slidably mounted therein, of a stop strip disposed contiguous to said sash at one side thereof, said stop strip being provided with spaced openings therein, and having recesses formed in the rear face of said strip extending laterally from the openings aforesaid towards the sash, a cup-shaped washer member mounted in the inner end of each of the openings aforesaid, the bottom wall of said washer member being provided with a transversely elongated slot, a fastening device extending through said slot and into said window frame, whereby to secure the stop strip to the frame in such manner as to permit lateral movement of the stop strip towards and away from said sash, and means for normally yieldably urging said stop strip towards said sash, said means comprising a coil spring mounted in each of the recesses aforesaid in the rear face of the stop strip, one end of the coil spring abutting against its associated fastening device and the other end operatively engaging said stop strip.

4. The combination with a window frame having a sash slidably mounted therein, of a stop strip disposed contiguous to said sash at one side thereof, said stop strip being provided with spaced openings therein, and having recesses formed in the rear face of said strip extending laterally from the openings aforesaid towards the sash, a cup-shaped washer member mounted in the inner end of each of the openings aforesaid, the bottom wall of said washer member being provided with a transversely elongated slot, a fastening device extending through said slot and into said window frame, whereby to secure the stop strip to the frame in such manner as to permit lateral movement of the stop strip towards and away from said sash, means for normally yieldably urging said stop strip towards said sash, said means comprising a coil spring mounted in each of the recesses aforesaid in the rear face of the stop strip, one end of the coil spring abutting against its associated fastening device, and a socket mem-

ber also mounted in each of the recesses and adapted to receive the opposite end of the coil spring, said socket member being closed at one end to form a seat for the contiguous end of the spring and having an offstanding spur adapted to be embedded in the strip to cause the pressure of the spring to be transmitted to said strip.

5. A stop strip mounting assembly for window frames, comprising a cup-shaped washer having an elongated slot formed in the bottom wall thereof, a fastening device adapted to extend through said slot and into the window frame, a coil spring adapted to be mounted with its axis disposed at a substantially right angle to said fastening de-

vice and with one end in abutting engagement therewith, and a socket member for receiving the opposite end of said spring, said socket member being provided with an offstanding spur adapted to be embedded in the stop strip.

6. As a new article of manufacture, a spring socket for window stop strip mounting assemblies and the like, comprising a tubular body open at one end and closed at its opposite end, said body being provided with an integral spur at its closed end projecting laterally to one side of the body and adapted to be embedded in the stop strip.
